STEEL POST OILER CUP

Henry P. Witt, Napa, Calif.

Application June 18, 1945, Serial No. 600,080

3 Claims. (Cl. 189—32)

My present invention, in its broad aspect, has to do with improvements in oiler cups for steel fence posts, and like steel objects which are susceptible to rust and corrosion. I have found that when steel fence posts begin to rust, the fence wires attached to them also rust and in time must be replaced. By providing an improved oil cup for use on steel fence posts, and other steel objects. I am enabled to keep a fine film of oil on the surface, and in time the oil will collect dust and the like, building up a protective coating which will preserve the fence post and the wires attached to it. I have also found that by placing rags and waste in the cups, the oil will be fed in the proper quantities to form the desired film, and but a small amount of crank-case oil, for instance, a year will serve the purpose.

In carrying my invention into effect, and accomplishing the above and other objects, I attach a cup on the top of each fence post, or the cup may be formed integral with the post. Each cup has openings through which the oil seeps and is partially filled with rags and waste. My cup may be applied to any shape fence post and may be cheaply and quickly formed as a metal stamping and applied without special tools.

Other and equally important objects and advantages of my invention will be apparent from the following description and drawing, but it is pointed out that changes in form, size, shape, materials, and construction and arrangement of parts may be made and are within my broad inventive concept, and the scope of the appended claims.

In the drawing, wherein I have illustrated a preferred form of my invention:

Figure 1 is a view of a fence with the posts provided with my oil cup;

Figure 2 is a top plan view of one of my cups;

Figure 3 is a section on the line 3—3 of Figure 2;

Figure 4 is a section on the line 4—4 of Figure 3;

Figure 5 is a section showing a cup applied to an angle iron fence post;

Figure 6 is a section showing a cup applied to a U-shaped fence post;

Figure 7 is a vertical section of a modification with the post and cup formed integral; and

Figure 8 is a top plan view of the form shown in Figure 7.

In the drawing like characters of reference are used to designate like or similar parts:

The numeral 1 designates a conventional T-shaped steel fence post carrying the fence wires

My cup 3 has an upwardly opening bell-shaped

body 4 with the sides curved outwardly as at 5 part way and then parallel and straight as at 6 to the mouth 7 which has a beaded outwardly turned edge 8. At the bottom of the body is a depending collar 9 which is given a driving fit with the fence post as shown in Figures 2, 3, 4, 5 and 6, or which may be integral with the fence post as shown in Figures 7 and 8. Openings 10 along the sides and at the ends of the surface of the fence post permit the oil to seep down the fence post in a film. It will be noted that the film of oil collects dust and the like to form a protective coating 10a over the surface of the post. The end openings 11 are connected with the side openings 12 by webs 13. A form applicable to L-shaped fence posts is shown in Figure 5, and in Figure 6, the center web 14 filling in the U-shaped area of the post has small arms 15 contacting the post and spacing the openings 16. Cotton waste or rags 17, or other suitable material is placed inside each oil cup. In the form shown in Figures 7 and 8, the body 18 of the cup is integral with the post and has a bottom 19 covering the open end of the post which is cylindrical. Oil passes through a circular arrangement of small equally spaced openings 20 in the bottom adjacent the outer surface of the post.

From the foregoing, it is believed that the operation and advantages of my invention will be apparent, but it is again pointed out that interpretation of its scope should only be conclusive when made in the light of the subjoined claims.

I claim:

1. An oiling device for fence posts, comprising a cup-shaped body integrally formed on the upper end of the fence post and having a bottom and openings in the bottom adjacent the surface of the fence post, and waste material in the cup-shaped body to be saturated with oil.

2. An oiling device for steel fence posts, comprising a cup having an upwardly directed mouth and mounted on the upper end of a fence post, material in the cup to be saturated with oil, the bottom of the cup having openings adjacent the fence post for distributing a film of oil over the surface of the fence post to provide a protective covering said cup being extended to form a sleeve to engage about the upper end of the fence post said openings being formed inwardly of said sleeve to permit said oil to cover the surface of said post.

3. The invention as in claim 2 wherein the openings in the bottom of the cup are separated by webs engaging the surface of the fence post.

HENRY P. WITT.
